OIL BURNER

Frank Cozzoli, Plainfield, N. J.

Application June 23, 1932, Serial No. 618,988

5 Claims.

This invention relates to oil burners and particularly to an improved hearth therefor, the object being to provide an improved construction which is simple and which provides a quick carburetion of the oil.

Another object of the invention is to provide an improved hearth structure for oil burners wherein the heated portion of the hearth structure is supported and insulated in such a way that the heat is prevented from passing downwardly.

A further object, more specifically, is to provide a hearth structure for oil burners wherein a fire ring is presented having portions for directing unused oil to a discharge point, and fingers for producing a better mixture of the oil and air during the carburetting action.

In the accompanying drawing,—

Figure 1 is a vertical sectional view through the lower part of the furnace and a burner disclosing an embodiment of the invention.

Figure 2 is a sectional view through Figure 1 approximately on line 2—2.

Referring to the accompanying drawing by numerals, 1 indicates the lower part of a domestic furnace of any desired kind, as, for instance, an ordinary steam heating furnace now in common use. It will be understood that the burner embodying the invention may be used with this kind of furnace or other devices without departing from the spirit of the invention.

As illustrated particularly in Figure 1, the burner is provided with an electric motor 2 for driving the rotating oil-distributing head 3. The motor 2 and associated parts are all carried by a number of supports 3'. In the accompanying drawing only three supports have been shown but it is evident that more may be used, if desired. Each of the supports 3' is preferably placed on an asbestos pad 4 to reduce the noise. Each support 3' consists of a tubular member 5 having a threaded rod 6 slidably mounted therein and supported on the tubular member 5 by a nut 7 screwed onto the rod 6. A shoulder 8 is provided on rod 6, said shoulder acting as a support for the bracket 9 formed preferably integral with the casting 10 hereinafter fully described. A nut 11 acts to clamp the bracket 9 firmly against the shoulder 8, while the threaded reduced portion 12 extends upwardly and is formed with a socket carrying an asbestos cushion member 13 which fits into a socket 13 formed on an annular metal plate 14, which plate supports an annular ring 15 of fire clay, cement or other desired material which acts as a heat insulation. Plate 14 is provided with an annular flange 16 having a depending portion 17 which may act as a drip for directing the oil into the groove 18 in the casing 10. An annular drain ring 19 is fitted over the upper part of the central portion of ring 15 and is provided

with a flange 20 overlapping the flange 16. A fire ring 21 is provided and the oil is sprayed against it through the various nozzles or openings 22 formed in the head 3. The fire ring 21 is provided with a grooved annular portion 23 which merges into an upstanding inclined wall 24, and also into an inclined ring section 25, having an annular notch 26 into which one edge of the ring 19 fits, thus permitting oil from the groove 23 to flow on to the ring 19 without coming in contact with the cement or other filling 15. The upper part of the wall 24 of the ring 21 is provided with a number of slots 28' whereby air is permitted to more readily mix with the sprayed oil, and to thereby assist in producing perfect combustion.

After the burner has become heated to a proper temperature the flame will usually begin a short distance beyond the upper edge of ring 21 and extend upwardly, and usually in an arc-shaped path inwardly, so as to make an inverted bowl-shaped flame. An ignition device 27 is provided at a desired point, the same being shown in Figure 1 as a gas jet connected by suitable piping 28 to a suitable gas supply, though an electric device could be used if preferred. This gas jet 25 presents a small pilot flame 29 which will readily ignite the oil when the furnace is first started. After it is started the same will automatically ignite itself and burn as long as the parts are functioning properly.

The head 3 is adapted to rotate at a prescribed speed, the same being rigidly secured in any desired manner to a shaft 30 which is connected rigidly in any desired manner to an armature of the electric motor 2, which motor is bolted or otherwise secured to the casting 10. Small air vents 31 are provided in the casting 10 so as to keep the upper part of the motor cool. Air from the openings 31 passes through opening 32 of the drip ring 33 and mixes with the air from the annular passageway 34, which air may pass through the opening 35 into the head 3, and also through the opening 36 over plate 19 to the ring 21 for mixing with the oil in order to properly support combustion. The casting 10 is provided with a bracket 9 for each of the posts 3' and with an annular groove 18, said groove gradually changes from a shallow groove at one side to a deeper groove on the other side. At the deepest part of the groove there is provided a discharge opening for directing the oil to a discharge point.

From Figure 1, it will be noted that the oil passes into the burner through the supply pipe 39, said oil moving under any desired pressure, as, for instance, the pressure produced by gravity where the supply of oil is slightly above the head 3. The oil passing through pipe 29 passes through passageway 40 of the valve 41, and thence through passageway 42 to passageway 43, and then to pipe 44, which pipe extends upwardly and

through opening 35 so as to discharge into the annular groove or cup-shaped portion 45 of the bottom plate 46 of the head 3. When the burner is functioning properly, the oil will be quickly 5 thrown out through the apertures 22 through centrifugal action and also through the action of the various blades 47, which blades have a straight section 48 and a curved section 49. In this way the oil is sprayed as it leaves the apertures or nozzles 22 and strikes the wall 24 where it vaporizes and mixes with the air so as to be readily ignited during the functioning of the burner.

If for any reason too much oil is fed into the 15 burner or the burner should not function properly, the oil may readily drip from the groove 45 on to the ring 33 and in case the oil accumulates in groove 23, it may readily flow over the ring section 25 and the ring 19 so as to drop down 20 into the groove 18. Oil flowing in this path will eventually flow out through a suitable discharge opening.

When the burner is functioning properly oil is discharged at the desired rate into the groove 45, 25 and this oil with some air is forced by centrifugal action and the blades 47 outwardly with considerable force. The plate 46 is preferably rigidly connected with the blades 47 and is bolted or otherwise rigidly secured to the plates 67, which plates 30 in turn are riveted or otherwise rigidly secured to the central fitting 68. The central fitting is threaded or otherwise secured to the shaft 30 of the motor 2. In this way, the motor 2 supports the head 3 and also rotates the same. 35 Preferably, an asbestos pad or sheeting 69 is mounted on top of the plates 67 so that none of the oil or air can pass upwardly but must pass outwardly.

As heretofore mentioned, the passageway 34 40 permits sufficient air to enter to properly support combustion. However, sometimes it may be desirable to regulate the volume of air entering and when this is true, the regulating ring or damper 70 is moved. This regulating ring or 45 damper is an annular ring having an annular depending flange 71, the lower edge of which rests on a number of supporting pins 72. A manually actuated locking screw 73 is threaded into the flange 71 and presses against the casting 10 to 50 lock the air regulating ring 70 in any desired adjusted position. When the screw 73 is loose, it may be used as a handle for rotating more or less the ring 70. Preferably, there are three of these 55 cams carried by ring 70, though a greater or even less number might be used without departing from the spirit of the invention. When it is desired to reduce the passageway 34, the ring 70 is rotated until the cams 74 have been moved upwardly on the pins 72 sufficiently to raise the 60 ring 70 the desired distance to reduce the passageway 34. After the ring 70 has once been adjusted for a given quantity of oil and for a given pressure in which it is fed into the device, the ring is left alone until the oil is changed or some 65 other adjustment has been made. Ordinarily, the ring 70 after it has once been adjusted is left in place even though slightly different qualities of oil are used.

During the operation of the burner and after 70 it has been shut down, air continues to flow through the air passageway 34 to keep the lower castings and other parts cool. During the func-

tioning of the burner the passage of air through passageway 34 not only keeps the motor and other parts cool but permits the air to become warmed by reason of this contact with plate 14 so that it is appreciably warmed before it is mixed with the sprayed oil. In this way the heat is maintained at the desired point and coolness is also maintained at the desired point, namely, at and near the motor 2.

I claim:—

1. In a burner of the character described, a fire ring having a grooved lower portion and an upstanding wall notched on the upper edge for forming a plurality of spaced heat radiating fingers, a centrally apertured heat insulating plate 15 for supporting said fire ring, and a drain ring having a depending annular flange extending into the aperture in said plate and the periphery extending beneath the inner edge of said fire ring for draining excessive oil from the fire ring. 20

2. In an oil burner, a hearth structure including an annular metal plate, an annular cement ring carried by said plate and positioned to cover the plate and engage the side walls of the furnace in which the burner is mounted, an annular drain ring mounted on said cement ring and overlapping the first mentioned ring so as to drain through the central opening thereof, and a fire ring having an annular abutment resting against the edge of the drain ring, and a projection extending over part of the upper edge of the drain ring, said fire ring also having an upwardly and outwardly extending oil receiving wall merging into a plurality of substantially flaring fingers. 30

3. In an oil burner for furnaces, a hearth structure including an annular plate having an upstanding wall at its inner edge, a drain ring overlapping said upstanding wall, and a metallic fire ring overlapping the outer edge of said drain 40 ring, said fire ring including a grooved portion for receiving oil when the same fails to ignite, and an upwardly and outwardly extending notched portion for receiving and deflecting the oil upwardly, the notched portion acting to spread 45 the oil and oil vapor.

4. In an oil burner for furnaces, a hearth including a supporting structure, an annular heat insulating ring and a fire ring having a base portion resting on said heat insulating ring and an upwardly and outwardly inclined oil receiving 50 wall, the upper edge of said wall being notched to present spaced fingers, said fingers being narrow and thin compared to the thickness of the fire ring so as to quickly heat and thereby produce an increased carburetion of the oil and air at the upper edge of the fire ring. 55

5. In an oil burner, a metallic fire ring having a centrally positioned grooved portion, an outer wall having upstanding fingers and an inner wall having an inclined upper surface with a notch in the under surface thereof, a drain ring having its periphery fitting into said notch, a heat insulating ring positioned to support the fire ring and the drain ring, and means for supporting 60 said heat insulating ring, said means including a plate underlying the heat insulating ring with an annular portion extending upwardly through the center of the heat insulating ring into a position in contact with said drain ring. 65
